UNITED STATES PATENT OFFICE.

ALLEN OLSON, OF SAN PEDRO, CALIFORNIA.

INSIDE PIPE-WRENCH.

1,371,642.

Specification of Letters Patent. Patented Mar. 15, 1921.

Application filed July 2, 1920. Serial No. 392,560.

To all whom it may concern:

Be it known that I, ALLEN OLSON, a citizen of the United States, residing at San Pedro, in the county of Los Angeles and State of California, have invented new and useful Improvements in Inside Pipe-Wrenches, of which the following is a specification.

This invention is a pipe wrench arranged 10 to engage the end of a pipe between jaws abutting against the outside of the pipe, and extending within the pipe so as to abut against the inside thereof, respectively.

It is the object of the invention to provide a construction of this character extremely simple in operation and of simplified and inexpensive construction.

The invention will be readily understood from the following description of the accompanying drawings, in which—

Figure 1 is a side elevation of the wrench partly in longitudinal section showing the application thereof to the end of a pipe.

Fig. 2 is a transverse section on the line 25 2—2 of Fig. 1.

Fig. 3 is a longitudinal section on the line 3—3 of Fig. 1.

Fig. 4 is a side elevation of the inside jaw of the wrench.

30 The pipe which is to be engaged by the wrench is shown at 1. The wrench comprises a shank 2 having the inside jaw 3 extending longitudinally beyond the shank and eccentrically arranged relative to the longitudinal axis thereof, and the outside jaw 4 extending alongside jaw 3 and concentrically mounted upon shank 2 so that the shank and the inside jaw may be rotated relative to the outside jaw. By this arrangement it will be seen that when the outside jaw is positioned against the outer surface of the pipe end with the inside jaw received within the pipe end and the shank is rotated, the eccentrically arranged inside jaw

40 will be moved toward the outside jaw so as to firmly clamp the end of the pipe between said jaws.

Referring specifically to the practical embodiment of the invention as illustrated 50 in the drawings, the shank 2 is shown as having an end handle portion 5, a hexagonal portion 6 adapted to be engaged by a wrench or the like for turning the tool, a cylindrical bearing portion 7 beyond the hexagonal portion 6, an enlarged cylindrical bearing portion 8 beyond bearing 7 arranged to form an

annular shoulder 9, and the jaw 3, preferably, of cylindrical conformation projecting longitudinally beyond the enlarged bearing 8 eccentrically to the longitudinal axis of the 60 tool shank.

Gripping teeth 10 are, preferably, provided longitudinally of the jaw 3, said teeth being shown as received in V-shaped grooves 11 extending along the surface of jaw 3. 65 Each of the teeth are, preferably, rectangular in cross section with two sides thereof received in one of the V-shaped grooves and the other two sides projecting beyond the surface of jaw 3 to provide the engaging 70 edge of the tooth. The inner end of the tooth, preferably, terminates in a pin 12 received within a suitable recess 13 provided in the end of the enlarged bearing 8, and the outer end of the tooth is, preferably, angularly arranged as shown at 14 so that the edge 15 of the jaw 3 at the sides of the tooth may be bent downwardly over the angularly arranged end of the tooth for retaining 75 the latter within its groove. 80

The outer jaw 4 comprises a sleeve 16 rotatably mounted upon bearings 7 and 8 with an interior annular shoulder 17 provided in said sleeve abutting against shoulder 9 to prevent longitudinal displacement of the 85 outer jaw in one direction. A collar 18 is fixed upon bearing 7 in rear of sleeve 16 as by a set screw 19 in order to prevent longitudinal displacement of said sleeve in the opposite direction. The jaw proper of the 90 outer jaw is shown at 4^a as projecting from sleeve 16 beyond bearing 8 and parallel to the jaw 3, the engaging surface 20 of said jaw being, preferably, transversely curved to conform approximately to the curvature of 95 the pipe to be engaged by the tool.

It will thus be seen that I have provided an extremely simple construction forming a wrench adapted to have one of its jaws received within the end of a pipe and its 100 other jaw received over the outside of the pipe end, the parts being so arranged that when the shank of the wrench is rotated the inner jaw will be moved toward the outer jaw for firmly clamping the pipe between 105 said jaws.

Various changes may be made without departing from the spirit of the invention as claimed.

What is claimed is:

1. A pipe wrench comprising jaws adapted to extend within, and to be received

against the outside of a pipe, and means for shifting the jaws laterally relative to one another to grip said pipe.

2. A pipe wrench comprising jaws adapted to extend within, and to be received against the outside of a pipe, and means for turning the inner jaw so as to shift the same laterally toward the outer jaw for gripping said pipe.

10 3. A pipe wrench comprising jaws adapted to extend within, and to be received against the outside of a pipe, the inner jaw being eccentrically rotatable within the outer jaw so that said jaws may be moved laterally toward one another for gripping said pipe.

4. A pipe wrench comprising jaws adapted to extend within, and to be received against the outside of a pipe, means for shifting the jaws laterally relative to one another to grip said pipe, and jaw teeth extending lengthwise of said jaws for contact with said pipe.

20 5. A pipe wrench comprising a shank, a

collar rotatably mounted on the end of said shank, an arcuate jaw extending from one side of said collar outwardly from the end of said shank, and a jaw projecting from the end of said shank, which last mentioned jaw is eccentrically arranged with respect to the axis of said shank, and oppositely disposed with respect to the arcuate jaw.

25 6. A pipe wrench comprising a shank, a collar rotatably mounted on the end of said shank, an arcuate jaw extending from one side of said collar outwardly from the end 35 of said shank, a jaw projecting from the end of said shank, which last mentioned jaw is eccentrically arranged with respect to the axis of said shank, and oppositely disposed with respect to the arcuate jaw, and longitudinally disposed teeth inserted in the periphery of said eccentrically disposed jaw.

In testimony whereof I have signed my name to this specification.

ALLEN OLSON.
